UNITED STATES PATENT OFFICE.

FRANCIS COOPER, OF HORNSEY, LONDON, ENGLAND.

DESIGN FOR A CLINICAL THERMOMETER.

44,300.

Specification for Design.

Patented July 8, 1913.

Application filed June 13, 1912. Serial No. 703,574. Term of patent 7 years.

To all whom it may concern:

Be it known that I, FRANCIS COOPER, a subject of the King of Great Britain and Ireland, residing at 4 Millman Terrace, Tottenham Lane, Hornsey, London, England, have invented a new, original, and ornamental Design for a Clinical Thermometer, of which the following is a specification, reference being had to the accompanying drawing, forming part thereof.

The accompanying drawing is an elevation of a clinical thermometer embodying my design.

I claim:

The ornamental design for a clinical thermometer as shown.

FRANCIS COOPER.

Witnesses:

O. J. WORTH,
C. P. LIDDON.
